UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

RESISTANCE.

Application filed March 31, 1921. Serial No. 457,382.

To all whom it may concern:

Be it known that I, NILS D. LEVIN, a citizen of the United States, residing at Columbus, in the county of Franklin and State of Ohio, have invented certain new and useful Improvements in Resistances, of which the following is a specification, reference being had therein to the accompanying drawing.

My present invention relates to certain new and useful improvements in resistances adapted to use upon electric locomotives, traction cars, and the like, for the control of the electric motors by which such vehicles are actuated.

15 The especial object is to provide a light and compact resistance element which shall have high resistance and large heat radiating capacity coupled with great mechanical strength.

20 A further object is to provide improved means for supporting a reflexed ribbon resistance element having the qualities above specified.

The devices by which I attain this object 25 are fully set forth in the following specification and illustrated in the accompanying drawings of which

Fig. 1 is a side elevation of a resistance unit embodying this invention.

30 Fig. 2 is an end elevation of the device taken along the line II—II of Fig. 1.

Fig. 3 is a section taken along the line III—III of Fig. 1.

35 Fig. 4 is a fragmentary sectional view taken along the line IV—IV of Fig. 1.

Fig. 5 is a view similar to Fig. 3 showing a modified construction.

Like numerals refer to similar parts in the several figures.

40 In the drawings I have shown a resistance unit formed of a continuous, relatively wide, ribbon conductor 1, composed of a suitable alloy having high specific electrical resistance and capable of withstanding relatively

45 high temperatures. At uniformly spaced intervals along its length the conductor 1 is bent upon itself, in the direction of its width, each bend being a complete semicircle, to form a laterally flattened helecoid 2. The

50 helecoid 2 is suspended by one side upon a longitudinally extending horizontal rod 3, positioned concentric with the semicircular bends of the conductor. The ends of the rod 3 are secured in suitable apertures of the 55 supporting end frames 4 by the lock nuts 5

screw threaded to said rod. A sleeve 6 and spacing washers 7, formed of suitable dielectric material, insulate adjacent turns of the conductor 1 from each other and from the rod 3, and these parts are securely held in 60 position by clamping nuts 8 screw threaded to the rod 3. A similar rod 9, parallel with the rod 3, and provided with similar insulating sleeve and spacing washers, is held in position concentric with the lower semicircular bends of the conductor 1 by clamping nuts 10, screw threaded to said rod. The ends of the rod 9 project through vertically extending slots 11 in the end frames 4, thereby affording support against lateral displacement while permitting vertical movement in conformity with the expansion and contraction of the conductor due to its changes of temperature.

For convenience of manufacture the conductor 1 is formed in sections 12, 13 and 14 the ends 15 of which project upwardly beyond the rod 4 and are attached to terminal connectors 16 by which the sections are connected together and with the conductors of 80 the external circuits.

It is apparent that this construction is subject to wide variation without departure from the spirit of my invention. One such modification is shown in Fig. 5 wherein the 85 conductor 1 is built up of a plurality of relatively long bars 17 connected at their ends by relatively short bars 18 into a series which is functionally identical with the ribbon conductors above described and which 90 is mounted in substantially the same manner.

By the devices above described I have produced a compact and durable resistance unit of great heat radiating capacity which 95 may be subjected to a wide range of temperatures without producing lateral distortion of the resistance elements.

What I claim is:

1. In a resistance comprising a conductor 100 bent upon itself to form a laterally flattened helecoid, means to rigidly support one side of said helecoid, and means yieldable in the direction of longitudinal expansion and contraction of said conductor to 105 support the other side of said helecoid against lateral displacement.

2. In a resistance comprising a continuous relatively wide ribbon conductor bent upon itself in the direction of its width to 110

form a laterally flattened helecoid, means to rigidly support one side of said helecoid, and means yieldable in the direction of the longitudinal expansion and contraction of said conductor to support the other side of said helecoid against lateral displacement.

3. In a resistance comprising a continuous relatively wide ribbon conductor bent upon itself in the direction of its width each 10 bend being a complete semicircle and forming a laterally flattened helecoid, means to rigidly support one side of said helecoid, and means yieldable in the direction of the longitudinal expansion and contraction of 15 said conductor to support the other side of said helecoid against lateral displacement.

4. In a resistance comprising a conductor bent upon itself to form a laterally flattened helecoid disposed in a vertical plane with its 20 longitudinal axes extending horizontally, means to rigidly support the upper side of said helecoid, and vertically yielding means to support its lower side.

5. In a resistance comprising a continuous relatively wide ribbon conductor bent upon itself in the direction of its width to 25 form a laterally flattened helecoid disposed in a vertical plane with its longitudinal axes extending horizontally, means to rigidly support the upper side of said helecoid, and 30 vertically yielding means to support its lower side, against longitudinal displacement.

6. In a resistance unit comprising a plurality of similar bars secured at their ends 35 in spaced parallelism and connected together in series, means to rigidly support one end of each bar, and means yieldable in the direction of the longitudinal expansion and contraction of said bars to rigidly support 40 the other end of each bar against lateral displacement.

In testimony whereof, I affix my signature:

NILS D. LEVEN.
